[57] CLAIM

The ornamental design for a shoe-shaped product dispenser, as shown and described.

DESCRIPTION

FIG. 1 is a front elevation view of a shoe-shaped product dispenser showing my new design;

FIG. 2 is a top plan view thereof;

FIG. 3 is a bottom plan view thereof;

FIG. 4 is a right side elevational view thereof; and,

FIG. 5 is a rear elevational view thereof.

The broken line showing of the trigger sprayer in FIG. 4 is for illustrative purposes only and forms no part of the claimed design.
